BOTTLE STERILIZER

Martin W. Connors, Waterbury, Conn., assignor
to Paul R. Doran, Waterbury, Conn.

Application July 13, 1937, Serial No. 153,327

1 Claim. (Cl. 21—79)

This invention relates to bottle sterilizers, and more particularly to a device whereby a plurality of nursing bottles may be rapidly, efficiently, and thoroughly sterilized at the same time.

5 One object of this invention is to provide a sterilizer of the above nature adapted to support a plurality of bottles in inverted position within an ordinary kettle in which a liquid may be boiled, whereby the steam therefrom will displace the air 10 in the bottles and thoroughly sterilize them.

A further object is to provide a flanged bottle sterilizer which is adapted to rest upon the top edge of a kettle, saucepan, or like container to support a plurality of inverted nursing bottles 15 out of contact with the water being boiled therein, whereby the bottles will not become wet and sterilization will be accomplished by the steam arising from the boiling water.

A still further object is to provide a bottle sterilizer of the above nature which will be simple in construction, inexpensive to manufacture, easy to manipulate, compact, ornamental in appearance, and very efficient and durable in use.

With these and other objects in view there has 20 been illustrated in the accompanying drawing one form in which the invention may be conveniently embodied in practice.

In the drawing:

Fig. 1 is a perspective view of the bottle sterilizer as it appears in use upon a saucepan.

Fig. 2 is a top plan view of the same.

Fig. 3 is a sectional view of the same, taken on the line 3—3 of Fig. 2, looking in the direction of the arrows.

35 The improved bottle sterilizer of this invention comprises a dish-shaped plate 10 having a depressed flat center portion 11 in which a plurality (six in this instance) of spaced-apart circular apertures 12 are provided. The plate 11 has an annular horizontal rim 13 which is adapted to rest upon the top edge of a container, such as a saucepan 14, in which water or other liquid may be boiled, the depressed center portion 11 being disposed within a top opening 15 of the same. The intermediate section 16 of the plate 10 surrounding the depressed portion 11 is substantially vertical and provides an additional support for the necks of the bottles 17 to prevent them from 40 tipping over outwardly when they are inserted and placed within the apertures 12, as clearly shown in Fig. 1. The level of the water in the saucepan 14 is indicated at 19, and the bottle necks 18 are adapted to be located above said level 45 in a steam space 20.

Operation

In operation, the steam will rise from the boiling water in the saucepan 14 and enter the bottles 17, expelling the air therefrom, and thus quickly and thoroughly sterilizing said bottles without causing them to become wet. If desired, the nursing nipples, which have been removed from the bottles, will be dropped into the bottom of the saucepan and sterilized in the boiling water therein, simultaneously with the sterilization of the bottles.

According to some tests made by bacteriologists, typhoid, streptococcus, and other germs will be completely destroyed by the use of the present 15 invention, and in some instances, within the short period of ten minutes.

One advantage of the present invention is that it is not necessary that the intermediate cylindrical section 16 of the sterilizer plate fit the top 20 opening 15 of the saucepan closely, as the sterilizer plate will operate equally well with saucepans of various sizes larger than said cylindrical section, thus allowing for considerable variation in the size of the kettle which may be employed 25 therewith.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within 30 the scope of the following claim.

Having thus fully described the invention, what is claimed as new, and for which it is desired to secure Letters Patent, is:

In a device for sterilizing bottles having reduced necks, a plate-like member having an outer relatively wide horizontal rim adapted to seat upon the upper edge of a kettle of boiling water and also having a depressed center portion connected with said rim by a cylindrical section of substantial height, said depressed portion having a plurality of spaced-apart apertures therein located adjacent the outer edge thereof to cause the necks of a plurality of inverted bottles inserted through said apertures for admitting steam to the interior of said bottles to lie against the inner edge of said rim to support said bottles in outwardly inclined positions.
